Primary Examiner—Stacia Cadmus*Attorney, Agent, or Firm*—Thompson Hine & Flory LLP[57] **CLAIM**

The ornamental design for a wheel cap, as shown and described.

DESCRIPTION

FIG. 1 is a perspective view of the wheel cap of my design; FIG. 2 is a top plan view of the wheel cap of FIG. 1; and, FIG. 3 is a side elevational view of the wheel cap of FIG. 1, it being understood that the opposite side is a mirror image thereof.

The broken lines shown in FIGS. 1 and 3 of the drawings are for illustrative purposes only and the subject matter depicted thereby constitutes no part of the claimed design.
